UNITED STATES PATENT OFFICE.

WILLIAM H. ROGERS, OF BATAVIA, NEW YORK, ASSIGNOR TO MERGENTHALER LINOTYPE COMPANY, A CORPORATION OF NEW YORK.

TYPOGRAPHICAL MACHINE.

1,092,171.

Specification of Letters Patent.

Patented Apr. 7, 1914.

Application filed January 18, 1913. Serial No. 742,797.

To all whom it may concern:

Be it known that I, WILLIAM H. ROGERS, a citizen of the United States, residing at Batavia, in the county of Genesee and State 5 of New York, have invented certain new and useful Improvements in Typographical Machines, of which the following is a specification, reference being had therein to the accompanying drawing.

- 10 My invention relates to typographical machines, such as linotype machine of the general organization represented in Letters Patent of the United States, No. 436,532, to O. Mergenthaler, wherein circulating matrices 15 are released from a magazine in the order in which their characters are to appear in print and then assembled in line, the composed line transferred to the face of a mold, the mold filled with molten metal to form a slug 20 or linotype against the matrices which produce the type characters thereon, and the matrices thereafter returned through a distributing mechanism to the magazine from which they started.
- 25 More particularly, it relates to the means for releasing the matrices, and is designed to effect the conjoint actuation of a plurality of escapements by the operation of a single key or the like, when desired.
- 30 In the accompanying drawing, I have shown my invention in preferred form and by way of example, and as applied to the form of keyboard mechanism presented in Letters Patent of the United States to O. Mergenthaler, No. 531,266, and to P. T. Dodge, 35 No. 530,931. However, it will be understood that many variations and alterations may be made therein, and in its mode of application, which will still be comprised with- 40 in its spirit. Thus, it may be applied to other forms of escapements, and of escapement-actuating devices, and to other styles of typographical machines, such for instance as type setters, type casters and the like.
- 45 Generally speaking, I desire it to be understood that I do not limit myself to any specific form or embodiment, except in so far as such limitations are specified in the claims.

Referring to the drawing: Figure 1 is a 50 detached perspective view, partly in section, of the escapement actuating mechanism, having my invention applied thereto; Fig. 2 is a front view, showing the connecting means in a specific form; Fig. 3 is a similar view, 55 with the parts in different position; and Fig.

4 is an edge view of a pair of compound matrices.

The matrices X are stored in a magazine A, their release therefrom being controlled by the escapements B, which are actuated by the reeds C, cam yokes D, cams E, rolls F, triggers G, slides H, and key levers J, in the manner well understood in the art, and substantially as presented in the previously-mentioned Letters Patent. It will be noted 60 that the keyboard and escapement-actuating mechanism illustrated are thus of the ordinary type, whereby the escapements may be actuated individually, each by the operation of its appropriate key. My invention not 65 only preserves this capability, but also affords means whereby two or more of the actuating devices may be connected at will to secure their conjoint operation.

In the use of these machines, it is sometimes necessary and desirable that matrices be simultaneously or successively released from a plurality of channels, and consequently that the escapements thereof be actuated together. For instance, in the case 75 of compound matrices, as shown in Fig. 4, where the characters are of unusual extent, and therefore have to be divided between two or more matrices, they must be successively and immediately delivered, and preferably by the operation of a single key. My improvements are, of course, similarly 80 applicable for other purposes, such as for running quads, leaders, and other matrices used for filling out extended spaces. 90

I preferably provide one or more of the slides H with pivoted arms or members K, which may be swung laterally to engage studs L on the adjacent or other slides H', so that when a slide H is moved in the ordinary manner, the slide H' will be shifted therewith, and through the connections previously described, the corresponding escapements B will be conjointly actuated. As 95 will be understood by those skilled in the art, in order to minimize the liability of transposition, the members K may be formed as shown in the drawing, of such size and proportion as to permit some lost motion, that is to say, to allow the slide H to move to a certain extent before the slide H' is shifted thereby. In this way, the actuation of the escapements B is not entirely simultaneous, and consequently the matrices are released 100 with an interval between them, so that one 105

may pass to the line before the other. In order that this connection and disconnection may be conveniently accomplished, I preferably employ a transversely movable sliding element M, suitably mounted in the framework, it being formed with recesses or notches N to engage projecting pins O on the arms or members K; whereby the manual adjustment of the slide M permits the operative connection and disconnection of the escapement-actuating devices at will.

As previously stated, I have shown my improvements only in preferred form and by way of example, and obviously many changes and modifications may be made therein without departure from their scope. Thus, the precise construction of the connecting members and their adjusting means, and their exact location and relation to the other parts, are all unessential to the practice of my invention. For instance, the members K might be connected to the reeds C instead of to the slides H, with the same result and effect; or my invention may be applied to reeds directly operated from the keys, instead of in connection with power-driven mechanism, as illustrated. Similarly, the same principle may be carried to any extent desired, and is not confined to the form shown, wherein only alternate slides H are shown as provided with the members K; as when necessary, these members may be duplicated and arranged so as to effect the conjoint actuation of three or more escapements, instead of two only, as illustrated. These and many other variations will suggest themselves to those skilled in the art.

Having thus described my invention, its construction and mode of operation, what I claim and desire to secure by Letters Patent of the United States, is as follows:

1. In a typographical machine, the combination of a pair of escapements and a corresponding pair of devices to actuate them individually, with means carried by one of said devices and laterally adjustable at will into direct engagement with the other; whereby the operation of one of said devices effects the conjoint actuation of both escapements.

2. In a typographical machine, the combination of a pair of escapement actuating devices, means carried by one of said devices and movable laterally into direct engagement with the other so as to connect the two together, and devices operable at will for moving said connecting means.

3. In a typographical machine, the combination of a pair of escapements and a corresponding pair of devices to actuate them individually, one of said devices being provided with a member movable laterally into direct engagement with the other; whereby the operation of one of said devices effects the conjoint actuation of both escapements. 65

4. In a typographical machine, the combination of a pair of escapements B, and means to actuate them individually, comprising the pair of slides H, H', one of said slides being provided with a laterally movable member K to engage directly a stud L on the other slide; whereby the operation of one of said devices effects the conjoint actuation of both escapements. 70

5. In a typographical machine, the combination of a pair of escapements B, and means to actuate them individually, comprising the slides H, H', one of said slides being provided with the laterally movable member K to engage directly a stud L on the other slide, together with the element M to shift the said member K. 75

6. In a typographical machine, the combination of a plurality of independently operable escapement actuating devices and a second corresponding plurality of escapement actuating devices connected to the several actuating devices of the first plurality; whereby the operation of any one of the actuating devices of the first plurality will effect the conjoint operation of an actuating device of the other plurality. 85 90

7. In a typographical machine, the combination of a series of escapements, a corresponding series of actuating devices therefor, and separate means for connecting said devices in a plurality of pairs; whereby the operation of an actuating device of each pair will effect the conjoint operation of its companion and the consequent actuation of 100 both escapements. 95

8. In a typographical machine, the combination of a series of escapement actuating devices, members carried by a plurality of said devices and movable laterally into direct engagement with other actuating devices, and a shifting element common to all of said members. 105

In testimony whereof I affix my signature in presence of two witnesses.

WILLIAM H. ROGERS.
